CLOTH LAYING MACHINE

Henry W. Bax, Glendale, N. Y.

Application October 15, 1953, Serial No. 386,208

6 Claims. (Cl. 270—31)

The invention herein disclosed relates to cloth laying machines.

Objects of the invention are to provide a machine of this character which will lay and fold the cloth smoothly and accurately and which will be of relatively simple construction and adapted to be produced at reasonable cost.

Particular objects of the invention are to improve the fold forming and the lifter and catcher mechanisms.

Other desirable objects and the novel features of construction, combination and relation of parts through which the purposes of the invention are attained, are set forth and will appear in the course of the following specification.

The drawings accompanying and forming part of the specification illustrate a present commercial embodiment of the invention. Structure, however, may be modified and changed as regards the immediate illustration, all within the true intent and scope of the invention as hereinafter defined and claimed.

Fig. 1 in the drawings is a broken side elevation of the machine;

Fig. 2 is a broken sectional view of the carriage and right-hand catcher on a larger scale, and showing the cloth gripped in the catcher and the carriage travelling to the left;

Fig. 3 is a further enlarged broken sectional view illustrating details of the automatic lift mechanism;

Figs. 4 and 5 are broken sectional detail views of the pawl and ratchet drive for the automatic lift mechanism;

Figs. 6 to 11 are broken sectional and somewhat diagrammatic views illustrating successive phases in the operation of spreading and folding the fabric;

Fig. 12 is a detail view with parts broken away, illustrating retracting movement of the left-hand catcher;

Fig. 13 is a broken part sectional plan of the retracting toggle mechanism.

In the general view, Fig. 1, a cloth spreading table is indicated at 15, having tracks 16 for the wheels 17 of the cloth carrying carriage 18.

Fold catchers 19, 20 are located at opposite ends of the table. These are alike so that the description of one will suffice for both.

The carriage is shown as having open bearings 21, 22 for the shaft 23 carrying the roll of cloth 24.

Figs. 1 and 2 show the path of the unwinding cloth upward and over the succession of guide rods or rolls 25, 26, 27, 28, 29 to the main guide roller 30, from whence it passes downward between the left and right feeder or folder blades or bars 31, 32.

These feeder bars are shown carried by dependent arms 33, 34, pivotally supported at their upper ends at 35, 36 on supporting bars 37 attached to brackets 38 which are guided up over parallel rods 39 and raised and lowered by screw shafts 40.

The upright screw shafts 40 at opposite sides of the

2

carriage are turned in unison through the medium of a cross shaft 41 having bevel gears 42 in mesh with bevel pinions 43 on the upper ends of the shafts.

A crank 44, Fig. 5, on one end of the cross shaft 41 enables vertical adjustments to be effected by hand and automatic lift operation of this shaft is effected through the medium of a ratchet 45 fast on the shaft, engageable by a pawl 46, Figs. 3 and 5, pivoted at 47 on an arm 48 pivotally hung at one end on the shaft 41 and pivotally connected at the opposite end by a link 49 with a horizontal slide 50.

Actuation of this ratchet turning slide is effected in the illustration from a push-rod 51 slidably mounted in the base of the carriage, in position to engage adjustable stops 52, 53 at opposite ends of the carriage travel and having the lower end of a rock lever 54 pivotally connected therewith at 55, this lever being pivoted on the carriage at a point intermediate its ends, at 56, and connected at its upper end through the medium of a swinging link 57, screw threaded and provided with nuts 58 adjustably engaging the upper end of the lever.

The pivoted pawl is shown as weighted to normally engage the ratchet so that upon each complete reciprocation of slide 50 the folder blades will be automatically lifted an amount determined by the setting of the adjustable connection at 58. At any time, however, the weighted pawl may be held disengaged from the ratchet and the crank 44 be turned to raise or lower the frame carrying the folder blades.

30 The catchers consist in each instance of a vertically operable clamp bar 59 having a corrugated rubber or similar frictional gripping surface 60 and a companion lower angular gripping member 61.

The clamp bars 59 are shown carried by brackets 62 secured in spaced parallel relation by stay-rods 63 and pins 64 sliding in vertical slots 65 in the stationary catcher frames 66.

Lifting of the catcher clamp bars is effected by inclined cam tracks 67, 68 on the carriage, positioned to underlie the rollers 69 on the outer sides of brackets 62.

These inclined cam tracks 67, 68 are shown carried by arms 70, 71 dependent from pivotal supports 72, 73 on the supporting bars 37, so that they may swing upward to pass over the rollers 69 after effecting the lifting and allowing the lowering of the clamp bars.

55 The feed bars 31, 32 are supported directly opposite with the cloth extending in a partial fold between the same. With travel in the left-hand direction, Fig. 2, the right-hand blade 32 will engage and form the turn in the cloth, and with travel in the opposite direction the left-hand blade 31 will effect the similar, reverse function.

50 These blades are supported directly opposite in closely adjoining relation and the forward blade, direction of motion considered, is the inactive one. To get this forward, inactive blade out of the way of the blade which is carrying the fold into the grip of the catcher, special means are provided in the form of ramps or cam slopes 74 on the brackets 62, engageable by rollers 75 on the swinging arms 33, 34 carrying the folder blades. These arms, as shown in Fig. 2, normally rest against stops 76 and the inclined tracks 67, 68 forming the lifters for the catchers, are supported in the lowered position by engagement of the arms 70, 71 with inclined shoulders 77 on brackets 38.

In the machine illustrated the left-hand catcher is made retractile to clear the end of the completed stack. This feature is illustrated in Figs. 12 and 13, where the 70 catcher is shown mounted on rollers 86 riding on tracks 87, maintained in this relation by overstanding guard flanges 88.

A cross shaft 89 journaled in stationary bearings 90 carries a hand crank 91 at one end and is equipped with rocker arms 92 pivoted at their ends, at 93, to drag links 94 pivotally connected with the frame of the catcher at 95. The rocker arms 92 and links 94 constitute toggles which can carry over from an extended position, Fig. 1, locking the catcher in the forward, operative relation, to the position shown in Fig. 12, approximately a swing of 180°, locking the catcher withdrawn clear of the end of the stacked material and leaving this end free and clear for subsequent operations.

Operation

With movement of the carriage to the left, the stretch of fabric held by the right-hand catcher will be carried forward, as shown in Figs. 1, 2 and 6, by blade 32, and toward the end of such movement rollers 75 of the forward blade 31 will engage and ride up the ramps or inclines 74 of the left-hand catcher to lift this blade, as shown in Figs. 7 and 8, clear out of the path of active blade 32.

In this same movement, as shown in Figs. 7, 8 and 9, the catcher lifter cam tracks 67 will engage rollers 69 and lift the upward-sliding side brackets 62 carrying the upper clamp bar 59.

In the latter part of such movement the lifting rollers 69 ride off the upper ends of inclined tracks 68, over onto stationary lugs or ledges 78 on the brackets 38, then, as shown in Figs. 8 and 9, dropping over the inner edges of these ledges to lower the bar 59 into clamping engagement over the fold of cloth then carried by bar 32 into position between the upper and lower clamp members 59 and 61.

With the fold completed and held in the left-hand catcher, the carriage motion is reversed as indicated by the arrow in Fig. 10, to withdraw the feed bar 32 and leave the fold gripped by clamp bar 59. The rubber facing and the weight of this clamp member enable it to hold the fold without slipping and without injuring the cloth.

At the time of reversal of movement the left-hand feed bar 31 commences to lower over the lifting cam 74, as indicated in Fig. 10, and this bar as it is completely lowered, as shown in Fig. 11, carries the cloth forward in the right-hand direction into the grip of the right-hand catcher which operates in the same manner last described.

The movement of the carriage may be effected by hand or power, hand operation being usually preferred, to suit the speed and the operation in general to the character of cloth being handled. In any event, the operation is smooth and uniform and precision results are attained.

The cloth is held firmly in the grippers without injury or marking, the sponge rubber facings of the clamp bars gripping the material with a yielding touch.

Additional yielding effect may be provided by mounting the gripper bars in yielding fashion, as by suspending them with bolts 79 from an angle bar support 80 connecting the blade lifting ramps 74, springs 81 surrounding the bolts permitting yielding upward movement and adjustment of the bolts limiting the extent of downward movement.

Manual lifting of the clamp bars may be effected at any time through the medium of hand levers 82, Fig. 2, pivoted on the catcher frames at 83 and having forked inner ends 84 engaged over the stay-rods 63 connecting the opposite ramps.

The carriage is shown as having a shelf or platform 85, Fig. 1, to facilitate placing of the rolls or bolts of cloth in the bearings provided for the same.

The clamp bars are automatically caught and held in the fully lifted relation shown in Fig. 2, by means of latches or dogs 96 pivoted on the frames of the catchers at 97, in position across the guide slots 65 so as to be struck by the stay-rods 63 in the lifting movement of the latter, and to then drop back to enable the supporting

shoulders 98 to catch beneath the rod. To release, it is then only necessary to apply pressure on the lifting lever 82 to take the weight off the latch and to then rock the latch to carry the supporting shoulder clear of the cross rod.

What is claimed is:

1. In a cloth laying machine having a spreading table, a cloth laying carriage mounted to travel back and forth over said table and catchers at opposite ends of the travel of said carriage, fold clamping bars vertically movable in said catchers, means on the carriage and catchers operable to lift and then lower said clamping bars in the end travel of the carriage in each direction, cloth folding blades pivotally hung on said carriage in spaced relation facing each other for passage of the cloth downwardly therebetween and positioned to carry successive folds of cloth beneath the upraised fold clamping bars and cooperating means on the carriage and catchers for lifting the forward folding blade, the direction of carriage movement considered, clear of said clamping bars prior to entry of the other folding blade beneath the upraised fold clamping bar in the travel of the carriage in each direction, a push-rod in the base of the carriage, stops on the table engageable by said push-rod in the travel of the carriage in opposite directions, a rock lever actuated by said push-rod, a slide adjustably connected with said rock lever, a pawl actuated by said slide, a ratchet engageable by said pawl, a shaft turned by said ratchet, upright screw shafts operable by said shaft and arranged to impart lifting movement to said cloth folding blades, said pawl being weighted and pivoted so as by such weight to be held in engagement with the ratchet whereby at any time the pawl may be manually held disengaged from the ratchet, and a crank on said shaft to facilitate manual turning of the shaft while the pawl is held disengaged from the shaft.

2. In a cloth laying machine having a spreading table, a cloth laying carriage mounted to travel back and forth over said table and catchers at opposite ends of the travel of said carriage, fold clamping bars vertically movable in said catchers, means on the carriage and catchers operable to lift and then lower said clamping bars in the end travel of the carriage in each direction, swing arms pivotally mounted on and suspended from the carriage, stop means for holding said arms in downwardly converging extension while permitting either of said arms to be swung upward so as at its lower end to clear the lower end of the other arm, cloth folding blades fixed on said arms at their lower ends in spaced relation facing each other for passage of the cloth downwardly therebetween and positioned to carry successive folds of cloth beneath the upraised fold clamping bars and cooperating means on the carriage and catchers for swinging upward the forward swing arm, the direction of carriage movement considered, thereby swingingly to lift the forward folding blade clear of said clamping bars prior to entry of the other folding blade beneath the upraised fold clamping bar in the travel of the carriage in each direction, said means for effecting the lifting and lowering of the fold clamping bars comprising abutments connected with the clamping bars, inclined tracks on the carriage to engage beneath said abutments on the movement of the carriage toward the catchers, said tracks being of a length to pass beyond the abutments and permit the abutments to drop off the upper ends of the tracks in the movement toward the catchers and said tracks being pivotally supported on the carriage so as to pass over the tops of the abutments on reverse movement of the carriage away from the catchers, there being a pair of swing arms pivotally mounted on and divergently suspended from the carriage, said tracks being fixed on the last-named swing arms, stationary ledges on the carriage at the upper ends of said tracks positioned to temporarily support the abutments after the upper ends of the tracks have passed from beneath the abutments and stop means for holding the last-named

arms to a predetermined minimum divergence, said ledges being on said stop means.

3. In a cloth laying machine having a spreading table, a cloth laying carriage mounted to travel back and forth over said table and catchers at opposite ends of the travel of said carriage, fold clamping bars vertically movable in said catchers, means on the carriage and catchers operable to lift and then lower said clamping bars in the end travel of the carriage in each direction, cloth folding blades pivotally hung on said carriage in spaced relation facing each other for passage of the cloth downwardly therebetween and positioned to carry successive folds of cloth beneath the upraised fold clamping bars and cooperating means on the carriage and catchers for lifting the forward folding blade, the direction of carriage movement considered, clear of said clamping bars prior to entry of the other folding blade beneath the upraised fold clamping bar in the travel of the carriage in each direction, hand levers pivotally mounted in the catchers and connected to lift the fold clamping bars independently of the means aforesaid and a pivoted latch dog for detaining said fold clamping bars in the fully elevated position to which they are lifted by said hand levers, said dog having a handle manually swingable to release the fold clamping bars from detention by the dog.

4. In a cloth laying machine having a spreading table, a cloth laying carriage mounted to travel back and forth over said table and catchers at opposite ends of the travel of said carriage, one of said catchers being mounted for travel toward and away from the carriage and toggle means for advancing and retracting said catcher and for retaining the catcher in the position to which it has been advanced toward the carriage.

5. In a cloth laying machine having a spreading table, a cloth laying carriage mounted to travel back and forth over said table and catchers at opposite ends of the travel of said carriage, said catchers having vertical guide slots, stay-rods guided in said slots, fold clamping bars connected with said stay-rods, hand levers pivoted on the catchers and connected with said stay-rods and latches releasably engageable with said stay-rods for supporting the stay-rods and attached fold clamping bars in vertically lifted relation.

6. In a cloth laying machine having a spreading table, a cloth laying carriage mounted to travel back and forth over said table and catchers at opposite ends of the travel

of said carriage, fold clamping bars vertically movable in said catchers, means on the carriage and catchers operable to lift and then lower said clamping bars in the end travel of the carriage in each direction, swing arms pivotally mounted on and suspended from the carriage, stop means for holding said arms in downwardly converging extension while permitting either of said arms to be swung upward so as at its lower end to clear the lower end of the other arm, cloth folding blades fixed on said arms at their lower ends in spaced relation facing each other for passage of the cloth downwardly therebetween and positioned to carry successive folds of cloth beneath the upraised fold clamping bars, cooperating means on the carriage and catchers for swinging upward the forward swing arm, the direction of carriage movement considered, thereby swingingly to lift the forward folding blade clear of said clamping bars prior to entry of the other folding blade beneath the upraised fold clamping bar in the travel of the carriage in each direction, said means for effecting the lifting and lowering of the fold clamping bars comprising abutments connected with the clamping bars, inclined tracks on the carriage to engage beneath said abutments on the movement of the carriage toward the catchers, there being a pair of downwardly extended and diverging swing arms, said tracks being fixed at the lower ends of the last-named swing arms and being of a length to pass beyond the abutments and permit the abutments to drop off the upper ends of the tracks in the movement toward the catchers and said last-named swing arms being so pivotally mounted as to permit said tracks to pass over the tops of the abutments on reverse movement of the carriage away from the catchers, a frame guided for vertical movement in the carriage and means operable in the movement of the carriage in opposite directions to lift said frame, both said pairs of swing arms being hung from said frame.
